Isidor Roth,
BY EVERETT BROOK ATTORNEYS.

UNITED STATES PATENT OFFICE.

ISIDOR ROTH, OF BROOKLYN, NEW YORK, ASSIGNOR TO BENJAMIN & JOHNS, A CORPORATION OF NEW JERSEY.

BRASSIÈRE

Application filed May 28, 1923. Serial No. 642,147.

This invention relates in general to brassières, and more particularly to brassières especially designed for wear with the modern low corset and including an upper bust supporting portion and a lower "diaphragm" supporting portion the front part of which is substantially inelastic and connected to the front part of said upper portion and the back part of which is elastic and separate from the back part of said upper portion.

The primary object of the invention is to provide such a brassière with a deep back or one which extends below the waistline, and yet will neatly fit and adjust itself to the body, particularly stout figures. It is also an object of the invention to provide a new and improved construction for the back of the brassière, and connection thereto of the front of the brassière, so that said back part at all times snugly and comfortably fits the waist of the wearer and conforms to the movements of the body, such as bending or stooping, thereby preventing the brassière from slipping out of place or becoming otherwise disarranged or wrinkled.

Further objects are to provide a brassière of this character in which the back is formed of substantially inelastic material with the upper part inelastically connected with said upper front portion of the brassière and the lower part elastically connected to the inelastic lower front "diaphragm" supporting portion of the brassière whereby said lower portion of the back may yield circumferentially of the body to snugly fit and adjust itself to the waistline of the wearer and prevent the back from sliding up or wrinkling, at the same time in no way affecting the substantially inelastic characteristic of the upper portion of the brassière or the function of the lower "diaphragm" supporting portion, and to obtain other results and advantages as may be brought out by the following description.

Referring to the accompanying drawings, in which the same reference characters designate corresponding and like parts,

Figure 1 is a perspective view of a brassière embodying my invention, viewing the same from the front and as applied to a human figure, the back of the brassière being illustrated as reflected in a mirror;

Figure 2 is a view of the outside of the brassière extended;

Figure 3 is a view similar to Fig. 2, showing the inside of the brassière;

Figure 4 is a transverse sectional view taken on line 4—4 of Fig. 3, looking in the direction of the arrows, and

Figure 5 is a fragmentary sectional view taken on line 5—5 of Fig. 3.

In the specific embodiment of the invention shown in the drawings, the reference character A designates the front of the brassière formed with upper and lower edges a and b shaped to conform to the human figure when the brassière encircles the same, and B the back of the brassière which is preferably formed in two sections of substantially inelastic material. The upper part of each section of the back B has one edge inelastically secured to one side edge of the front A from the upper edge thereof to a point spaced from the bottom edge, as at 1, and elastically secured to said front A for the remainder of its length, as at 2, whereby the lower part of the back of the brassière may yield circumferentially of the body independently of the upper part of said back and the front A. The other edges of said back sections are provided with parts of separable fasteners, such as hooks and eyes 3, for securing the brassière on the body, and the upper edge of the brassière is provided with shoulder straps 4 or the like.

The lower front portion 5 of the brassière is adapted to overlie the upper edge of the front of a corset C, Figure 1, and is preferably formed of substantially inelastic material which will resist considerable tension and is somewhat wider at its center than at its ends 5^b, the upper edge curving downwardly from said center 5^a to the ends 5^b; also the central part of this lower portion 5 is preferably stiffened, as by stays 6. This lower portion 5 is designed to support the "diaphragm" of the wearer, the ends of said lower portion being free from the back of the brassière and having secured thereto strong elastic belt sections 7 which are slightly narrower than said ends and adapted to connect at their ends at the back of the wearer, as by means of hooks and eyes 8 or other suitable fasteners. It will be understood that by the term "diaphragm" in the trade is meant that portion of the wear-

er's flesh, particularly in stout persons, which tends to bulge outwardly over the top edge of the modern low bust corsets which terminate at their tops substantially at the 5 wearer's waistline. This bulging flesh or "diaphragm" detracts from the appearance of the wearer, but is pressed back into place and supported by means of the "diaphragm" supporting portion 5. The belt sections 7 lie 10 over the upper part of the corset at the back of the wearer, as shown more especially in Figure 1, and give the proper tension to the inelastic portion 5 at the front of the brassière.

15 The upper front portion 9 of the brassière is preferably constructed of material which is substantially inelastic circumferentially of the body but which will yield or stretch in an up and down direction sufficiently to conform to the bust. The lower edge of said upper front portion is secured to the upper edge of the lower "diaphragm" supporting portion 5, as at 10, and is formed with darts 20 11 or the like to shape the same to conform to and support the bust. As the garment is applied, the material in the upper section 11 will yield lengthwise of the body, and as the garment is drawn toward the back its inelasticity circumferentially will cause the 25 garment to snugly fit and conform to the bust so as to effectively support the same. This construction also ensures a smooth and unwrinkled condition of the garment and consequently a neat appearing and comfortable brassière.

30 Each section of the back B of the brassière is preferably formed of two pieces of material 12 and 13 secured together as at 14 in any suitable manner, as by stitching, the upper pieces 12 each having one edge inelastically secured to one side edge of the upper front portion for its full length at 1, while each of the lower pieces 13 has its inner end secured to the lower "diaphragm" supporting portion 5 by means of an elastic strip 2 or the like which is free from the upper front portion 9 at its edge adjacent thereto. The lower pieces 13 are also preferably shaped and formed with a fullness to permit them 35 to conform to the waist and the hips of the wearer. The back sections are preferably provided with stiffeners 15.

35 The brassière is applied to the body from the front in the usual manner and the fasteners 3 on the back sections B connected, with the lower edges of the back overlying the top of the corset C. In this operation the elastic strips 2 are placed under tension, by connecting the fasteners on the lower pieces 13 of the back, so that said lower pieces are drawn into snug and smooth engagement with the corset. The belt sections 7 are then connected by the fasteners 8, said belt sections being thus placed under tension to

cause the "diaphragm" supporting portion 65 5 to snugly engage the front of the upper portion of the corset and provide the desired support for the diaphragm. These belt sections 7 are unconnected with the back B of the brassière but lie upon the lower pieces 13 70 of said back, said belt sections thus assisting the tension of the strips 2 in holding the said lower pieces 13 from slipping off the corset, and drawing and holding the brassière as a whole into proper relation to 75 the corset, thus ensuring the "diaphragm" supporting portion being always in proper position to perform its functions. The elastic strips 2 permit the lower parts 13 of the back to yield circumferentially of the 80 body independently of the upper parts 12 to conform to the movements of the wearer, such as bending or stooping, at the same time holding said back from sliding or becoming wrinkled and in no way affecting the 85 functions of the upper front portion 9 or the "diaphragm" supporting portion 5.

90 While I have shown and described one preferred embodiment of my invention, it will be understood that this is only for the purpose of illustrating the principles of the invention and that many modifications and changes can be made in the detail construction of the brassière without departing from the spirit or scope of the invention. Therefore, I do not desire to be understood as limiting myself, except as required by the 95 following claims when construed in the light of the prior art.

Having thus described the invention, what 100 I claim is:

1. In a brassière, the combination of a front upper portion, a front lower inelastic diaphragm-supporting portion disposed transversely of the garment, a back part extending from the side edges of said front upper portion around the back of the wearer for substantially the entire height of both said front portions, and elastic connecting means for said diaphragm-supporting portion in alignment therewith to extend around the back of the wearer and being otherwise free from the garment.

2. In a brassière, the combination of a front upper portion, a front lower inelastic diaphragm-supporting portion disposed transversely of the garment, a back part extending from the side edges of said front upper portion around the back of the wearer for substantially the entire height of both 110 said front portions and having its lower part elastically connected to said diaphragm-supporting portion, and elastic connecting means for said diaphragm-supporting portion in alignment therewith to extend around the back of the wearer and being otherwise free from the garment.

3. In a brassière, the combination of a

- front upper portion, a front lower inelastic diaphragm-supporting portion disposed transversely of the garment, a back part extending from the side edges of said front upper portion around the back of the wearer for substantially the entire height of both said front portions, and elastic connecting means for said diaphragm-supporting portion in alinement therewith to extend around the back of the wearer, said connecting means being otherwise free from the garment and outside the said back part thereof.
4. In a brassière, the combination of a front upper portion, a front lower inelastic diaphragm-supporting portion disposed transversely of the garment, a back part extending from the side edges of said front upper portion around the back of the wearer for substantially the entire height of both said front portions and having its lower part elastically connected to said diaphragm-supporting portion, and elastic connecting means for said diaphragm-supporting portion in alinement therewith to extend around the back of the wearer, said connecting means being otherwise free from the garment and outside the said back part thereof.
5. In a brassière, the combination of a front upper portion, a front lower inelastic diaphragm-supporting portion disposed transversely of the garment, a back part extending from the side edges of said front upper portion around the back of the wearer for substantially the entire height of said front portions, elastic strips connecting the lower parts of the side edges of said back part to said diaphragm-supporting portion at distances from its extremities, and elastic belt sections extending from said extremities of the diaphragm-supporting portion

tion around the back of a wearer and being otherwise free from the garment.

6. In a brassière, the combination of a front upper portion, a front lower inelastic diaphragm-supporting portion disposed transversely of the garment, a back part extending from the side edges of said front upper portion around the back of the wearer for substantially the entire height of said front portions, elastic strips connecting the lower parts of the side edges of said back part to said diaphragm-supporting portion at distances from its extremities, and elastic belt sections extending from said extremities of the diaphragm-supporting portion around the back of the wearer, said belt section being otherwise free from the rest of the garment and outside the said back part thereof.

7. In a brassière, the combination of a front upper portion, a front lower inelastic diaphragm-supporting portion disposed transversely of the garment with its ends in alinement with the side edges of the said upper portion, a back part extending from the side edges of said front upper portion around the back of the wearer for substantially the entire height of said front portions, elastic strips connecting the lower parts of the side edges of said back part to the inside of said diaphragm-supporting portion at distances from its extremities, and elastic belt sections extending from said extremities of the diaphragm-supporting portion around the back of a wearer, said belt sections being otherwise free from the rest of the garment and outside the said back part thereof.

ISIDOR ROTH.
